Assistant Examiner — Jamaal Rasheed

(57) **CLAIM**

The ornamental design for a set of toilet rim-blocks, as shown and described.

DESCRIPTION

FIG. 1 is a top, front, right perspective view of a set of toilet rim-blocks showing our new design in its exemplary environment;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines showing a set of toilet rim-block holder depicts environment which forms no part of the claimed design.

1 Claim, 5 Drawing Sheets
